Attn:

UNITED STATES PATENT OFFICE.

JULIUS A. BIDWELL, OF POMONA, CALIFORNIA.

DESIGN FOR A CUFF-BUTTON.

SPECIFICATION forming part of Design No. 21,902, dated October 18, 1892.

Application filed August 16, 1892. Serial No. 443,266. Term of patent 7 years.

To all whom it may concern:

Be it known that I, JULIUS A. BIDWELL, a citizen of the United States, residing at Pomona, county of Los Angeles, State of California, have invented and produced a new and original Design for a Cuff-Button, of which the following is a specification, reference being had to the accompanying drawing, forming a part thereof, which represents 10 a front elevation of a cuff-button embodying the features of my design.

The design consists of a circular figure A, represented with a second circular figure B arranged concentrically upon its surface, where- 15 by the design may be said to consist in a cir-

cular figure apparently embossed concentrically upon a second underlying circular figure, the one overlying the other.

The second adjunctive feature of the design consists in the representation of the dollar sign (\$) upon the smaller overlying circular figure. 20

What I claim is—

The design for a button, substantially as herein shown and described.

JULIUS A. BIDWELL.
